UNITED STATES PATENT OFFICE.

CLAUDE B. STOCKSTILL, OF HUGOTON, KANSAS.

RAILWAY-CROSSING GATE.

1,260,090.

Specification of Letters Patent. Patented Mar. 19, 1918.

Application filed June 26, 1917. Serial No. 177,094.

To all whom it may concern:

Be it known that I, CLAUDE B. STOCKSTILL, a citizen of the United States, residing at 5 Hugoton, in the county of Stevens and State of Kansas, have invented new and useful Improvements in Railway-Crossing Gates, of which the following is a specification.

This invention relates to gates, and more especially to those which are mounted on horizontal pivots and interconnected and mechanically operated; and the object of the same is to produce improved means for automatically opening and closing the gates 15 across a highway and its side path at a point where the same cross a railway track—the closing being automatically done by an approaching train and the gates reset to open position after the train has passed.

20 This object is carried out by the construction hereinafter more fully described and claimed and as shown in the drawings wherein:—

Figure 1 is a plan view showing a diagrammatic arrangement of parts, and indicating at one side an approaching train and the position to which it swings the lever.

Fig. 2 is an elevation of the parts of this device at the crossing, the gates being shown 30 open in full lines and closed in dotted lines.

Fig. 3 is an enlarged detail of the inner ends of the two gate-members and the parts connecting them, this view showing all parts in one position; and Fig. 4 is a sectional 35 view on the line 4—4 of Fig. 2, with the parts in the other position.

In Fig. 1 of the drawings I have shown the railway track at R, crossing a highway H and footpath F, and have indicated a 40 train T approaching on the track. At either side of the highway and perhaps two-hundred yards therefrom is disposed a lever, respectively numbered herein as 1 and 2, each pivotally mounted on an upright post 45 3 alongside the track and having its inner end upturned at 4 and adapted to be struck by a projecting portion 5 of the locomotive or the forward car of a train. The disposition of the levers and their upturned ends 50 and of the projection on the locomotive is such that as the train approaches it swings one lever inward, and after having passed the highway it strikes the other lever and swings it outward, both for purposes hereinafter set forth. I may here say that the 55 elements hereinafter referred to as "cords" will doubtless be wires or small cables, or perhaps chains, inclosed in tubing or boxing which may be carried on posts at a slight distance above the ground or may be buried 60 but which of course will have to be buried where it passes across the highway, and the pulleys diagrammatically shown in Fig. 1 will be incased and protected in similar manner so as to preclude the possibility of 65 interference by unauthorized persons and to exclude the weather as is well understood. Also I would explain that, although I have shown this gate mechanism as arranged at one side of the track R only, and alongside 70 a single track railway, it is quite obvious that it could be duplicated on the other side of the same and the actuating mechanism could be arranged for operation by a train moving in either direction and on either 75 track. Yet further, the small gates which close across the footpath F would, in that case, close across the same footpath on the other side of the railway, or across another 80 footpath if the same existed at the other side of the highway H. With this explanation it is sufficient to state that a cord 6 leads from the outer end of the lever 1, a short distance away from the post, around a pulley 7, thence back across the highway and footpath F to the corresponding end of the other lever 2, thence on and around a second pulley 8, and back to the point of starting: thus 85 producing a complete loop between the corresponding ends of the two levers and causing the movement of one in one direction 90 to produce the movement of the other in the other direction. The result is that when the upturned end of one lever is moved inward toward the highway the corresponding end of the other lever is also moved inward: then when the train passes across the highway and footpath and the upturned end of the second lever is moved outward or away 95 from the highway, the upturned end of the opposite or first-named lever is also moved outward away from the highway and the parts reset for subsequent operation in a manner which will be explained. The loop 100 which has just been described may be completely inclosed within the housing or tubing along with the pulleys mentioned, excepting where the cord leaves the housing for connection with the ends of the levers. The distance of the latter from the highway 110 is of course unimportant, but I consider two hundred yards sufficient.

Alongside the highway stands a post 10 to which at 11 is pivoted the main gate 12, this gate being preferably a bar having an outer arm long enough to reach completely across the highway, painted some bright color so that it may be seen at a distance, and preferably having a signal as explained below; and also having a short arm inside its pivot. Adjacent the post is 10 the second post 13 to which at 14 is pivoted the small gate 15, the same also preferably having a longer arm adapted to reach across the footpath F and a shorter arm adjacent the shorter arm of the main gate, 15 overlying the same. These shorter arms are connected by an upright pivoted link 16, and the link or its pivots may carry suitable weights 17 which are sufficient to normally retain the gates in open position. Attached to the proper strand of the loop of 20 cord above described is an actuating cord 18 which passes under a pulley 19 and upward to the outer end of the long arm of the smaller gate, or if not to the extreme outer 25 end thereof, then to some point on the same which corresponds with the movement of the levers above mentioned. Now when an approaching train strikes one lever and swings it in the manner above suggested, the loop 30 causes the simultaneous swinging of the other lever, the actuating cord is drawn upon, and both gates are swung on their pivots to closed position. The counterbalancing weight rises, and the gates remain in this 35 position while the train is passing from the lever first struck, across the highway H and footpath F, and to and past the other lever. The latter being struck by the projection on the locomotive, is moved in the 40 opposite direction, and the gates are reset to open position—all without attention on the part of anyone.

In connection with this improved railway crossing gate I make use of signals, 45 which may be visible or audible or both. The audible signal may be a bell actuated electrically or otherwise and tripped by an approaching train and cut out by the same train after it has passed on, but this detail 50 is not illustrated—merely suggested. The visible signal is shown in the drawings, and its wiring is diagrammatically illustrated. It consists of a lamp in the shape of an electric bulb 20, carried on the long arm of the 55 main gate and connected by wire 21 with the battery 22. The other wire 23 leads from said battery to a terminal 24 which may be carried by the post 10. A second

terminal 25 is connected by wire 26 with the bulb and supported by the long arm of the gate. When now this arm descends as above explained, the two terminals come into contact and the circuit is closed and the bulb lighted. I would have the terminals rather long and yielding as shown, so 60 that contact is made and the bulb is lighted as the arm is descending, and the light is displayed at both sides of the arm as long as the latter is down or even partway down. The result is that—whether the audible signal is used or not—as soon as the gate begins to close the light or lights are illuminated and an approaching driver knows that the gate-arm is about to descend. Therefore he is given warning in time to stop 70 his team at some little distance from the gate, and it closes across the highway in front of him. The train now approaches and passes, and afterward the gate rises and the light is automatically extinguished, so 80 that the driver may pass on. The same occurs simultaneously with the other gate swinging across the footpath F, but it is hardly necessary to provide a duplicate light on this gate, although the same may be 85 provided if desired. Thus is produced an automatic gate and signal which needs no attention after once it is installed, excepting that occasionally the battery must be replenished and the wiring inspected. With 90 the visible signal and certainly with both visible and audible signals, it is hardly necessary to duplicate the gate at the other side of the railway, because the single gate can be clearly seen across the track by a 95 driver approaching from the opposite direction; but yet at busy points it may be wise to duplicate the construction here shown, and I reserve the right to do so if desired. 100

What is claimed as new is:

A highway gate for railroad crossings comprising a gate arm, means for normally holding the same in raised position, levers pivoted intermediate their ends adjacent the track and having one end adapted to be struck by a train, a pulley located in the rear of each lever, a cord connected with the end of one lever and passing around the pulley adjacent the other lever and connected to the end of said other lever, then passing around the second pulley to the starting point, and a second cord connecting the gate arm with one of the levers. 105

In testimony whereof I affix my signature. 110
CLAUDE B. STOCKSTILL.
